US00D962051S

(12) **United States Design Patent** (10) Patent No.: **US D962,051 S**
(45) Date of Patent: **** Aug. 30, 2022**

(54) **CONTAINER**

(71) Applicants: **Direct Pack, Inc.**, Azusa, CA (US);
Tanimura & Antle Fresh Foods, Inc.,
Salinas, CA (US)

(72) Inventors: **John Michael Pessagno**, Salinas, CA
(US); **Kevin-Dirk Pesirla Closas**,
Ontario, CA (US); **Scott Daniel
Grabau**, Hollister, CA (US); **Eric
Wexler**, Salinas, CA (US); **Ashley
Megan Pipkin**, Marina, CA (US);
Donald Edward Klusendorf,
Monterey, CA (US); **Gurmail S.
Mudahar**, Salinas, CA (US)

(73) Assignees: **Direct Pack, Inc.**, Azusa, CA (US);
Tanimura & Antle Fresh Foods, Inc.,
Salinas, CA (US)

(**) Term: **15 Years**

(21) Appl. No.: **29/725,659**

(22) Filed: **Feb. 26, 2020**

(51) LOC (13) Cl. **09-03**

(52) U.S. Cl. **D9/425**
USPC ....

CLAIM

The ornamental design for a container, as shown and described.

DESCRIPTION

FIG. 1 is a top, front perspective view of a container showing our new design;

FIG. 2 is a top, rear perspective view thereof;

FIG. 3 is a front elevational view thereof;

FIG. 4 is a back elevational view thereof;

FIG. 5 is a right elevational view thereof, the left elevational view being a mirror image of the right elevational view;

FIG. 6 is a top plan view thereof; and,

FIG. 7 is a bottom plan view thereof.

1 Claim, 7 Drawing Sheets
